DESIGN FOR A SOUND TRANSLATING DEVICE

Gabriel M. Giannini, Great Neck, N. Y., assignor
to Automatic Electric Company, Chicago, Ill.,
a corporation of Delaware

Application February 6, 1939, Serial No. 82,796

Term of patent 14 years

To all whom it may concern:

Be it known that I, Gabriel M. Giannini, a citizen of the United States of America, residing at Great Neck, Long Island, in the county of Nassau, New York, have invented a new, original, and ornamental Design for a Sound Translating Device, of which the following is a specification, reference being had to the accompanying drawing, forming a part thereof.

Figure 1 is a front perspective view; Fig. 2 is a side elevational view, and Fig. 3 is a rear elevational view of a sound translating device, showing my new design.

I claim:

The ornamental design for a sound translating device, as shown.

GABRIEL M. GIANNINI.
